UNITED STATES PATENT OFFICE.

PERCY HORACE LETCHFORD AND GEORGE HENRY SALTMARSH, OF WINNIPEG, MANITOBA, CANADA.

HEADLIGHT-DIMMER.

1,377,711.

Specification of Letters Patent. Patented May 10, 1921.

Application filed February 5, 1919. Serial No. 275,265.

To all whom it may concern:

Be it known that we, PERCY HORACE LETCHFORD and GEORGE HENRY SALTMARSH, both of the city of Winnipeg, in the Province of Manitoba, Canada, have jointly invented certain new and useful Improvements in Headlight-Dimmers, of which the following is the specification.

The invention relates to improvements in headlight dimmers and the principal object of the invention is to provide a dimmer for a headlight which, when applied, will provide a good driving light on the roadway but will not glare in the eyes of the pedestrian or other drivers.

A further object of the invention is to provide a dimmer which can be manufactured in a durable and inexpensive manner and which can be readily installed in position in the headlight and which, when installed, cannot rotate out of position.

A still further object is to construct a dimmer so that it can be readily cut down to fit the varying sizes of headlights now commercially sold.

With the above objects in view the invention consists essentially in a mask plate and a reflector associated with the plate, the parts being arranged and constructed as hereinafter more particularly described and later pointed out in the appended claims, reference being had to the accompanying drawing in which:—

Figure 1 represents a vertical sectional view through a headlight showing our dimmer installed.

Fig. 2 represents a front view of the dimmer.

Fig. 3 represents a perspective view of the dimmer as it appears mounted in the glass rim and looking at it from the interior.

Fig. 4 represents a detailed horizontal sectional view through one of the spring clips of the rim.

In the drawing like characters of reference indicate corresponding parts in the several figures.

1 represents a mask plate provided centrally with an upward extension 2 and at the edges with notches 3 and 4. The mask plate is utilized for cutting off the direct rays as well as the reflected rays of light from the lamp and can be opaque or translucent as wished. The radius of the plate is somewhat greater than the inner radius

of the headlight rim on which it is applied and the extension 2 is made such that when the dimmer is properly placed in the rim the extension covers the lamp from view.

To the rear side of the mask plate we attach in any suitable manner a substantially U-shaped rearwardly extending and downwardly inclining reflector 5 which is designed to extend beneath the light and practically touch the reflector of the headlight.

In order that the invention may be better understood we have shown a headlight, now described, and the dimmer associated with it.

6 represents the reflecting surface of the headlight and 7 represents the rim carrying the usual glass 8 which glass is customarily held in position by a number of spring clips 9 mounted on the rim and holding the glass firmly in place.

The dimmer is placed in position by removing the rim with glass and placing the dimmer against the glass on the rear side and with the notches 3 and 4 receiving the clips as best shown in Fig. 3. This arrangement not only effects the holding of the dimmer in place behind the glass but prevents the dimmer from rotating.

In referring to Fig. 1 it will be observed that the upper edge 10 of the extension lies slightly above the upper side of the lamp 11, the tip of the lamp being actually centered in respect to the extension, this being best shown in Fig. 2 where the light is indicated in dotted outline. Further, in these latter two figures it will be seen that the reflector 5 lies directly underneath the lamp and is for the greater part concentric to the lamp.

When this device is in use there is a good driving light on the roadway and there is positively no glare.

By making the mask large enough to accommodate a large sized glass frame it is possible for one to cut it down to fit the smaller sizes as occasion may demand.

What we claim as our invention is:—

1. The combination with a headlight comprising a parabolic reflector, a lamp located at the focal point of the said reflector and a closure glass inclosing the front of the reflector, of a semi-circular mask plate fitting against and covering the lower inside half of the closure glass and provided with an upward semi-circular extension located in the plane of the plate and of greater radius

than the lamp and positioned directly in front of the lamp and a substantially semi-circular reflector carried by and inclining downwardly and extending inwardly from the central part of the plate to a point adjacent the parabolic reflector and surrounding the under half of the lamp.

2. The combination with a headlight comprising a casing, a closure glass closing the front of the casing, a rim and spring clips holding the glass in the rim, of a semi-circular masked plate adapted to fit against and cover the lower inside half of the headlight closure glass, said masked plate being disposed with its straight edge uppermost and having its curved edge notched adjacent to each end to receive the spring clips holding the closure glass in place, the upper straight edge of the masked plate being extended in-

termediate of its length to provide a projection disposed directly in front of the headlight lamp bulb, and a reflector of substantially semi-circular cross section fixed at one end to the inside of the masked plate and inclining inwardly and downwardly therefrom to a point adjacent the reflecting wall of the headlight casing, said reflector being positioned below and partially inclosing the lower half of the lamp bulb so as to deflect upwardly the light rays emanating therefrom. 20 25 30

Signed at Winnipeg, this 15 day of January, 1919.

PERCY HORACE LETCHFORD,
GEORGE HENRY SALTMARSH.

In the presence of—

G. S. ROXBURGH,
K. B. WAKEFIELD.
